United States Patent Office.

R. F. BOCEMSDES, OF WALLINGFORD, CONNECTICUT.

Letters Patent No. 66,290, dated July 2, 1867.

IMPROVED BOTTLE-STOPPER.

The Schedule referred to in these Letters Patent and making part of the same.

TO ALL WHOM IT MAY CONCERN:

Be it known that I, R. F. BOCEMSDES, of Wallingford, New Haven county, Connecticut, have invented a new and improved Bottle-Stopper; and I do hereby declare that the following is a full, clear, and exact description thereof, which will enable others skilled in the art to make and use the same, reference being had to the accompanying drawings, forming part of this specification, in which the drawing represents my improved bottlestopper, as applied to a bottle.

The object of this invention is to provide a convenient and perfect stopper for bottles or decanters, and consists in an India-rubber cylinder of proper shape to fit the mouth and neck of the bottle or decanter, which is fitted around a metal tube for receiving a screw fastened into the head of the stopper. The stopper is inserted in the bottle when the screw is partly withdrawn, and the India-rubber cylinder is elongated by its elasticity so that it enters easily, and the screw is then turned for the purpose of compressing the India rubber and extending it laterally, so that it shall fit in the neck of the bottle tightly and fill the sides completely, effectually preventing the admission of air or the loss of the contents. The India-rubber stopper *a* is in cylindrical form, and is fitted to a metal tube, *b*, which is flanged at the lower end for the support of the bottom of the India-rubber cylinder *a*, the upper end of which is cut to receive a screw, *c*, fastened to or forming a part of the head *d*, which may also be made of metal or of glass, or any other suitable material. The head may be made hollow, in connection with the tube *b*, for pouring liquids from a bottle without removing the stopper. It is obvious that when the screw *c* is withdrawn from the tube *b*, the India-rubber cylinder *a* may be formed to expand and enter the mouth and neck of a bottle easily, while if the screw is screwed into the tube, the India-rubber cylinder will expand laterally by compression, and fit the bottle tightly.

Having thus described my invention, what I claim as new, and desire to secure by Letters Patent, is—

The tube *b*, the upper end cut to receive the screw *c* of the hollow head *d* having a hinged cap, the lower end flanged to support the rubber cylinder *a*, all constructed and arranged in such a manner that the liquid shall be discharged from the bottle without removing the stopper, as herein shown and described.

The above specification of my invention signed by me this 13th day of March, 1867.

R. F. BOCEMSDES.
